UNITED STATES PATENT OFFICE.

ISAAC NAYLOR, OF LOS ANGELES, AND HENRY B. RUGGLES, OF PASADENA, CALIFORNIA.

RECEPTACLE OR CONTAINER.

1,226,359.

Specification of Letters Patent.

Patented May 15, 1917.

Application filed July 9, 1914. Serial No. 849,874.

To all whom it may concern:

Be it known that we, ISAAC NAYLOR, of Los Angeles, in the county of Los Angeles and State of California, and HENRY B. RUGGLES, of Pasadena, in the county of Los Angeles and State of California, both citizens of the United States, have invented certain new and useful Improvements in Receptacles or Containers, of which the following is a specification.

Our invention relates to receptacles or containers and more particularly to barrels, casks, kegs, and similar vessels. The particular object of our invention is to produce a device of this character that is formed of a pulpos raw or crude waste material, properly treated, and molded or formed into the desired shape. A further object is to construct the receptacle or container in a manner so that it may be readily knocked down if desired, or if found expedient may be constructed of knocked down elements capable of being interlocked and sealed to form an integral device. Further objects are to construct a receptacle so that the same is extremely light in weight, inexpensive to manufacture, and is extremely strong in use.

These objects we prefer to accomplish by the means and in the manner hereinafter fully described and as more particularly pointed out in the claim, reference being had to the accompanying drawings forming a part of this specification, in which:—

Figure 1 is a vertical side elevation of a cask made in accordance with our invention showing the cover elevated therefrom;

Fig. 2 is a transverse section of a fragmentary portion thereof showing a manner of interlocking the cover;

Fig. 3 is a fragmentary view similar to Fig. 2 of a modified manner of interlocking the chime and cover of a cask;

Fig. 4 is a vertical side elevation of a barrel showing a manner of reinforcing the sides or bulge thereof.

Referring to Fig. 1 of the drawing, it will be observed that our receptacle is of a barrel or cask shape and comprises a body portion 1 with the usual bellied or bulged sides and constructed or formed in an in-

tegral unit. The material used in the construction of the body and other portions of the receptacle is raw or crude fibrous material reduced to a pulpos or doughy mass, 55 which mass is formed or molded into the shape of the finished receptacle. The upper and lower edges of the walls of the barrel are preferably flattened into a cylinder to form modified chimes 2 over which 60 the heads or covers 3 are adapted to be fitted. If desired, short threads 4 of abrupt pitch may be made on the exterior of the chimes and are adapted to fit into counterpart threads 5 formed in the outer face 65 of a groove or recess 6 made in the under side of the heads 3 so that when the latter are placed over said chimes a short turn will lock them in position. We prefer to increase the thickness of the heads adjacent their peripheral edges as shown at 7 and before the heads are finally placed on 70 the barrel a coating of pulpos material treated with adhesive substance is applied either in the groove 6 or upon the chime so 75 that when the parts are dried the heads will tightly fit together and render the joint air and water tight.

In Fig. 3 is disclosed a modified cover 8 and chime 9 therefor wherein the short 80 threads 10 are disposed upon the interior surface of the chime while the cover comprises a block the edge of which is vertically disposed and provided with exterior threads 11 adapted to engage threads 10. 85 A short angular lip or rim 12 extends around the upper corner of the head as shown so that when the head is disposed in proper position it will rest upon the upper edge of the chime as will be understood. 90

The fibrous material of which the receptacle is constructed possesses such properties that it is tough and has great tensile strength, yet it may be readily cut by a saw or an edged tool, and when so cut may 95 be readily united by the application, to the edges it is desired to join, of a coating of said material in a pulpos state and treated with adhesive substances.

It is obvious from the above that receptacles of various shapes or sizes and constructed integrally or in parts may be made

in the manner described and we do not desire to be limited to any particular shape, size or construction.

Having thus described our invention what we claim as new and desire to secure by Letters Patent, is:—

A barrel having an end of cylindrical form with longitudinally projecting teeth the side edges of which are inclined to provide inclined recesses, said teeth being in the plane of the body of the barrel, each terminating at the upper edge of the barrel and a head provided with a circumferential flange having spaced teeth alternating with those of the barrel and receivable in inter-

locking engagement within the recesses, the flange and barrel body being in longitudinal alinement.

In testimony whereof we each affix our signatures in the presence of two witnesses. 20

ISAAC NAYLOR.

HENRY B. RUGGLES.
